CLAIM

The ornamental design for a media streaming accessory, as shown and described.

DESCRIPTION

FIG. 1 is a front perspective view of a media streaming accessory showing our new design; FIG. 2 is a front elevational view thereof; FIG. 3 is a rear elevational view thereof; FIG. 4 is a left-side elevational view thereof; FIG. 5 is a right-side elevational view thereof; FIG. 6 is a top plan view thereof; and, FIG. 7 is a bottom plan view thereof.

The broken lines in FIGS. 1 and 7 depict portions of the media streaming accessory that form no part of the claimed design.

1 Claim, 4 Drawing Sheets

Related U.S. Application Data

continuation of application No. 29/737,185, filed on Jun. 5, 2020, now Pat. No. Des. 945,416.
